UNITED STATES PATENT OFFICE.

HENRY R. BREMER, OF KANSAS CITY, MISSOURI.

METAL-FLANGING MACHINE.

1,426,253.

Specification of Letters Patent. Patented Aug. 15, 1922.

Application filed August 8, 1921. Serial No. 490,678.

To all whom it may concern:

Be it known that I, HENRY R. BREMER, a citizen of the United States, residing at Kansas City, in the county of Jackson and State of Missouri, have invented certain new and useful Improvements in Metal-Flanging Machines; and I do declare the following to be a full, clear, and exact description of the invention, such as will enable others skilled in the art to which it appertains to make and use the same.

My invention relates to metal flanging machines and has for its object to provide a simple and efficient machine for forming a continuous flange on a sheet of metal by means of a die and rollers co-acting therewith, novel provision being made for constantly forcing the die toward a flange on one of the rollers which turns the flange on the sheet of metal around the edge of the die, the machine being intended principally for constructing can-box ends for truck tanks.

With the foregoing in view, the invention resides in the novel subject matter herein described and claimed, the descriptive matter being supplemented by the accompanying drawings.

Figure 1 is a side elevation, partly in vertical section, showing a flanging machine construction in accordance with my invention.

Figure 2 is an enlarged vertical section, partly in elevation, showing more particularly the flanging rollers, the die, and the spring-pressed shoe for holding said die in operative relation with the rollers.

Figure 3 is a plan view showing one shape of the die and illustrating the manner of securing a sheet of metal thereto.

Figure 4 is a sectional view as indicated by line 4—4 of Fig. 3.

Figure 5 is a sectional view of a sheet of metal flanged by the machine.

In the drawings above briefly described, the numeral 1 designates a horizontally elongated base from one end of which a casting or other suitable roller support rises, said support being preferably provided with an overhanging arm 3 whose free end carries a vertical guide way 4 in which a bearing box 5 is vertically movable by means of a suitable screw or the like 6. A shaft section 7 is rotatably mounted in the box 5 and is provided at one end with a flanging roller 8 whose inner edge is

equipped with a peripheral flange 9. The inner end of the shaft section 7 is connected by a universal joint 10 with an extensible and contractible shaft section 11 which is in turn universally connected at 12 to a shaft section 13 which extends through the arm 3, approximately at its juncture with the lower portion of the support 2. The outer end of the shaft section 13 is provided with a gear 14 meshing with another gear 15 on a horizontal shaft 16 which extends through the support 2, below the arm 3 and carries a stationary roller 17 disposed beneath the roller 8. The shaft 16 is provided with suitable driving means such as tight and loose pulleys 18 co-operable with a belt 19.

While certain specific details have been shown for mounting the roller 8 so that it may be moved vertically, and for driving both of the rollers 8 and 17 I wish it understood that any equivalent means could be provided and furthermore that the machine would operate in some instances if only one of the rollers were driven.

The end of the base 1, remote from the roller support 2, is provided with an appropriate die supporting means which is here shown in the form of upstanding flanges 20 extending across the base. Here again, however, it is to be understood that the die support may be of any adequate construction.

One form of die is shown in the drawings, being designated by the reference numeral 21, this die being in the form of a continuous bar forming an open frame. The shape of die shown is intended for forming flanges on sheets of metal 22 for use as can-box ends for truck tanks, but it will be understood that any shape of die may be used. The sheet 22 is secured upon the die 21 by any suitable means, such as a pair of screws 23 and with the roller 8 in a raised position, the die and sheet are then placed upon the supports 20 and roller 17. The roller 8 is then lowered and its flange 9 bends the first portion of the flange. By now driving one or both rollers 8—17 as the case may be, and continually forcing the die 21 toward the flange 9, this flange bends the projecting edge of the sheet 22 downwardly to form a flange thereon and at the same time feeds the die and sheet between the rollers.

For the purpose of holding the die and sheet always in proper relation with the flange 9 of roller 8, I provide a spring-

pressed shoe 24 engaging the inner edge of the die 21 as shown clearly in Figs. 1 and 2. This shoe is preferably in the form of a roller, mounted on one end of a horizontal 5 plunger rod 25 which is slidably supported by a pair of standards 26 rising from the base 1. The rod 25 as here shown, is provided with a collar 27 and a coiled spring 28 is interposed between this collar and one of 10 the standards 26. The collar 27 is by preference threaded upon the rod 25 so that the strength of the spring 28 may be controlled to insure that the shoe 24 shall at all times exert the necessary pressure on the die.

15 A machine constructed as or approximately as herein disclosed, will form a continuous flange on a metal sheet with much greater speed than the usual hand methods now employed and furthermore, a much smoother and better job is produced.

20 Since excellent results may be obtained by using the details shown, they may be followed if desired, but as above stated, numerous changes may be made and the present disclosure is therefore to be considered 25 for illustrative purposes only.

I claim:

1. A flanging machine comprising a pair of spaced rollers and driving means for at 30 least one of said rollers, means mounting said rollers with their axes in parallel relation, one of said rollers having a circumferential flange, a sheet-carrying die adapted to travel between said rollers, and means 35 for forcing said die continually toward the flange of said one roller.

2. A flanging machine comprising a pair of spaced rollers and driving means for at least one of said rollers, means mounting 40 said rollers with their axes in parallel relation, one of said rollers having a circum-

ferential flange, a sheet-carrying die adapted to travel between said rollers, a spring-pressed member mounted for movement toward said rollers in a direction parallel with 45 their axes, and a shoe carried by said member for forcing said die continually toward the flange of said one roller.

3. A flanging machine comprising a pair of spaced rollers and driving means for at 50 least one of said rollers, means mounting said rollers with their axes in parallel relation, one of said rollers having a circumferential flange, a sheet-carrying die adapted to travel between said rollers, said die 55 being continuous and in the form of an open frame of slightly less size than the sheet to be flanged, and means for supporting the frame and sheet while leaving them free to move under the action of the rollers. 60

4. A flanging machine comprising a base having an upwardly extending roller-supporting structure, a stationary roller mounted on said structure on a horizontal axis, a vertically movable flanged roller mounted on 65 said structure above said stationary roller, means mounted on said structure for raising and lowering said upper roller, means for driving at least one of said rollers, die supporting means rising from said base, an open 70 die forming frame adapted to be horizontally supported on said die supporting means and said stationary roller, said frame being adapted to carry the sheet to be flanged, a spring-pressed shoe for forcing said frame 75 toward the flange of said vertically movable roller, and means mounting said shoe on said base.

In testimony whereof I have hereunto set my hand.

HENRY R. BREMER.
